[57] CLAIM

The ornamental design for an automated apparatus for cutting rolled strips of transformer steel, as shown and described.

DESCRIPTION

FIG. 1 is a perspective view of an automated apparatus for cutting rolled strips of transformer steel and showing our new design;

FIG. 2 is a side elevation view taken from the left of FIG. 1;

FIG. 3 is a side elevation view taken from the right of FIG. 1;

FIG. 4 is a top plan view thereof;

FIG. 5 is a rear elevation view thereof; and

FIG. 6 is a front elevation view thereof.

The control unit shown in FIG. 1 has been omitted in the other views for ease of illustration; the rear of this unit is planar and unornamented.

FIG. 1

FIG. 2

FIG. 3

FIG. 5

FIG. 6
